VALVE FITTING

James A. Tiller, Louisville, Ky., assignor to American Radiator & Standard Sanitary Corporation, Pittsburgh, Pa., a corporation of Delaware

Application September 24, 1954, Serial No. 32,434

Term of patent 14 years

(Cl. D78—1)

Fig. 1

Fig. 2

Fig. 3

Fig. 1 is a view in side elevation of a valve fitting showing my new design,

Fig. 2 is a perspective view thereof, and

Fig. 3 is a view in front elevation thereof.

The characteristic feature of my design for a valve fitting disclosed resides in the handle portion having the configuration shown.

I claim:

The ornamental design for a valve fitting, substantially as shown and described.
